UNITED STATES PATENT OFFICE.

FRANK J. HESSE, OF WEST ORANGE, NEW JERSEY.

SAFETY GAS-VALVE.

1,196,455.

Specification of Letters Patent. Patented Aug. 29, 1916.

Application filed June 16, 1914. Serial No. 845,415.

To all whom it may concern:

Be it known that I, FRANK J. HESSE, a citizen of the United States, residing at West Orange, in the county of Essex and State of New Jersey, have invented certain new and useful Improvements in Safety Gas-Valves; and I do hereby declare the following to be a full, clear, and exact description of the invention, such as will enable others skilled in the art to which it appertains to make and use the same.

My invention relates to new and useful improvements in valves, and has particular reference to that type which are used in connection with illuminating gas burners, and are automatic in operation.

An important object of my invention is to provide a device of the above mentioned character, that is designed to eliminate the danger of loss of life by asphyxiation, as it is constructed to automatically lock and check the flow of gas to the burner upon the cutting off of the flow of gas at the gas tap, and to remain locked until released by the action of a spring pressed plunger.

A further important object of my invention is to provide a device of the above mentioned character which may be constructed of few parts, reliable in its operation, and cheap to manufacture.

The above and additional objects are accomplished by such means as are illustrated in the accompanying drawings, described in the following specification, and then more particularly pointed out in the claims which are appended hereto and form a part of this application.

With reference to the drawings, wherein I have illustrated the preferred embodiment of my invention as it is reduced to practice, and throughout the several views of which similar reference numerals designate corresponding parts: Figure 1 is a longitudinal sectional view of my device, showing the valve in its closed position, Fig. 2 is a side elevation, showing the valve in its open position, and Fig. 3 is a side elevation.

Proceeding now to the description of the drawings in which like numerals are employed to designate like parts throughout the same, the numeral 1 designates a cylindrical valve casing which is interposed between the burner designated B as an entirety, and the pipe 2 which communicates with the main pipe line, (not shown), and has operably connected therewith the ordi-

nary type of gas cock, also not shown. The lower terminal of the valve casing 1 is internally screw threaded to receive the screw threaded upper terminal 3 of a tubular valve section 4, which is provided at a point intermediate and essentially central of the ends with an annular flange 5 which is adapted to engage the lower terminal of and lie flush with the cylindrical casing 1. The lower terminal of the tubular valve member 4 is internally screw threaded to receive the screw threaded upper terminal 6 of the pipe 2. The upper terminal of the tubular valve member 4 is closed as indicated at 7, with the exception of a circular counter-sunk opening 8 which extends through the closed portion of the tubular valve member 4.

A plug valve 9 having a beveled head portion 10 and a reduced shank 11 is loosely mounted within the opening 8 and engages the side wall thereof for a distance equivalent to the length of the unreduced portion of the plug valve 9. The beveled head 10 of the plug valve 9 is adapted to seat within the counter-sunk opening 8.

Mounted upon the upper terminal of the tubular valve member 4 is a bifurcated curved supporting arm 12 which is provided centrally of its ends with an opening 13. Formed on the upper terminal of the supporting arm 12 are enlarged transverse apertured portions 14.

A depending locking bolt or arm 15 is pivotally mounted between the enlarged heads 14 of the supporting arm 12 by means of the pivot pin 16. Formed on the lower terminal of the depending arm 15 is an enlarged ball member 17, which is provided with a flattened surface 18 adjacent one side thereof, which is adapted to frictionally engage the rounded portion 19, formed on the free terminal of a movable bolt supporting and valve seating arm 20 which is pivotally mounted between the sides of the bifurcated arm 12 as indicated at 21. The ball member 17 is also provided at its under side with a flattened portion 18a, which is adapted to engage the ball member 19 and hold the same into engagement with the head 10 of the plug valve, to hold said valve in its closed position.

A boss 22 is formed on one side of the cylindrical valve casing 1, and is provided with an internally screw threaded opening 110 extending centrally therethrough, in which is adapted to be removably and slidably

mounted a plunger 23 which is provided intermediate its ends with an annular stop 24 to limit the outward movement thereof, and adapted to engage the screw threaded reduced portion 25 of a nut 26 which is threaded within the screw threaded opening of the boss 22 and loosely mounted upon the plunger 23, which provides for the slidable mounting of the plunger.

- 10 The inner terminal 28 of the plunger 23 extends through the opening 13 in the bifurcated supporting arm 12, and is adapted to engage the flattened surface 18 of the ball member 17 upon the inward movement of 15 the plunger 23 against the action of a helical spring 29, which is mounted upon the plunger 23 and engages at its respective terminals the enlarged head 27 and the nut 26. The action of the helical spring 29 is 20 such as to cause the inner terminal 28 of the plunger 23 to be normally spaced from the ball member 17, when the valve is in its closed position.

25 The operation of my device may be briefly described as follows: Assuming that the valve is in its closed position, as clearly indicated in Fig. 1, to open the valve, the plunger 23 is pushed inwardly, so that the free terminal thereof engages the flattened 30 surface 18 of the ball member 17 and forces it outwardly from engagement with the rounded portion 19, which action allows the valve 9 to be moved upwardly by the gas pressure. As the valve 9 moves upwardly, 35 it forces the rounded portion 19 into engagement with the ball member 17, and the flattened surface 18 on the ball member, serves to hold the rounded portion 19 out of engagement with the valve 9, whereby the 40 flow of gas will be continuous through the valve opening 8 and casing 1 and to the burner B as the pressure of the gas will hold the plug valve 9 out of engagement with the opening 8, and in a position supporting the rounded portion 19 out of locking engagement with the flattened surface 45 18^a on the ball member 17.

It is apparent with reference to the drawing that in order to lock the valve in its 50 closed position, to prevent the gas from escaping into the room, should the gas cock be accidentally turned on after the gas had been extinguished, the gas cock is turned to cut off the flow of gas to the burner, and 55 upon the diminution of the pressure the valve 9 and rounded portion 19 will drop automatically to a position which will close the valve and allow the member 19 to be engaged by the flattened surface 18^a of the ball member 17, thereby providing the desired 60 action.

In reduction to practice, I have found that the form of my invention, illustrated in the drawings and referred to in the above description, as the preferred embodiment, is 65 the most efficient and practical; yet realizing that the conditions concurrent with the adoption of my device will necessarily vary, I desire to emphasize the fact that various minor changes in details of construction, 70 proportion and arrangement of parts may be resorted to, when required, without sacrificing any of the advantages of my invention, as defined in the appended claims.

Having thus described my invention, what 75 I claim is:

1. A safety gas valve comprising a casing having inlet and outlet ports, a valve controlling the inlet port and adapted to be seated and held unseated by the pressure of 80 gas, an upright support located within the casing, a locking bolt pivoted to the upper end of the support and depending downwardly therefrom, the ends of said bolt terminating into a spherical head having 85 one side flattened, a bolt supporting and valve seating arm pivoted to the lower end of said support, the free end of which terminates into a spherical member to engage the flat face of the spherical head of the bolt 90 when said valve is unseated, and means by which the locking bolt may be moved into an inoperative position to permit of the unseating of said valve.

2. A safety gas valve comprising a casing 95 having inlet and outlet ports, a valve controlling the inlet port, and adapted to be seated and held unseated by the pressure of the gas, an upright support located within the casing, a locking bolt pivoted to the 100 upper end of and depending from the support, its free end terminating into a spherical head having one side flattened, a bolt supporting and valve seating arm pivoted to the lower end of the support having a 105 spherical head adapted to engage the upper face of the valve, means by which the locking bolt may be moved into inoperative position when the valve is unseated, the head of the valve seating arm engaging the front 110 face of the bolt whereby upon the seating of said valve the valve seating arm will be dropped and the spherical head of the bolt will abut the upper face of the head of the valve seating arm and hold the same locked 115 upon decrease of gas pressure.

In testimony whereof I affix my signature in presence of two witnesses.

FRANK J. HESSE.
